Angeles, Calif.

Application February 2, 1938, Serial No. 188,218

32 Claims. (Cl. 192—48)

This invention has to do with a clutch mechanism, and it is particularly directed toward the provision of a clutch mechanism operable by centrifugal action. Such a clutch is useful in automotive vehicles and the same is described herein in such an environment, but it will be obvious that the clutch mechanism may be employed elsewhere than in automotive vehicles.

One of the principal objects of the invention is, the provision of a centrifugal automatic clutch mechanism wherein a priming centrifugal clutching action initially takes place; wherein a secondary centrifugal clutching action comes into play thereafter at a higher R. P. M.; and wherein both the priming or initial and the secondary centrifugal actions operate collectively to pack the respective clutch engagements at a coefficient which will maintain a high torque capacity at an R. P. M. lower than that speed at which the secondary centrifugal clutching effect may respond to come into play.

Another object of the invention is, the provision of a centrifugal automatic clutch mechanism with a first distinct system of centrifugal acting means to start the clutch engagement-packing of a given system of clutchable elements and a second distinct system of centrifugal acting means for completing the clutch engagement-packing of the given system of clutchable elements, respectively, whereby the initial centrifugal clutching action is, for example, gradual in accordance with accelerating R. P. M. of the driving member and whereby the subsequent secondary centrifugal clutching action may be appreciably relatively faster in attaining a given torque capacity than that ordinarily required to centrifugally produce such torque capacity.

Another object of the invention is, the provision of a multi-clutch mechanism wherein a plurality of distinct centrifugal systems form means individually operative to cause certain clutch engagement packing and collectively operate to cause accumulated clutch engagement packing whereby at least a faster centrifugal-clutch-engagement-packing effective-pressure relative to a given R. P. M. may result, at least in the collective centrifugal clutching action, than that ordinarily responsive and proportionate to acceleration between given R. P. M.'s.

Another object of the invention is, the provision of a centrifugal automatic clutch mechanism provided with a multiple clutching system associated with a given initial acting system of clutch engagement-packing centrifugal means system and provided with a dead center toggle linkage

forming means whereby complete packing of the given multiple clutching system under the initial packing-centrifugal means is restrained until an abnormally high R. P. M. has been attained at 5 which the initial packing centrifugal means may have a coefficient such that, when released by the dead center toggle linkage, may immediately pack the entirety of the multiple clutching system at a full torque capacity. And, to the end of controlling the dead center toggle means, the present invention further contemplates the provision of a distinct system of speed responsive means together with a distinct system of resilient means collectively forming means for normally urging 10 the dead center toggle linkage into and to rest in dead center toggle relation whereby the restraining action which it is designed to effect is incurred, but to respond to a predetermined speed of rotation with the effect of causing the 15 collapse of the dead center toggle against the influence of the resilient means whereby the restraining effect of the toggle linkage is both timed and actuated out of play.

Another object of the invention is, the provision of a centrifugal automatic clutch mechanism provided with a multiple clutching system associated with a given initial acting system of clutch engagement-packing centrifugal means and provided with an expandable unit of frictionally-engaging elements connected to rotate as a unit but arranged and adapted to normally standstill and be initially engaged by a priming frictionally-engaging driving clutch element thereto. The latter to be actuated by the given 20 associate system of initial acting centrifugal means, whereby the normally still unit of expandable clutch elements may be excited to rotate from a standstill up to the speed of the engaging driving member immediately and accordingly immediately develop a high torque 25 clutching capacity. And, to the end of developing said high torque capacity in the unit of expandable clutch elements under this immediate speed attainment from a standstill corresponding to the speed of the driving member, the present invention further contemplates the provision of a distinct system of centrifugal weights carried by, and for causing the expanding of, the unit of expandable clutch elements whereby the centrifugal clutch packing coefficient corresponding to the speed of a priming driving member may be reached as rapidly as that of the rate of acceleration of the unit of expandable clutch elements 30 from their state of standing still to their primed 35

rotation up to the speed of the driving and clutching primer.

Another object of the invention is, the provision of a multi-clutch mechanism, provided with speed responsive automatic means for clutch engagingly packing first one and later another of the clutchable units of the multi-clutch mechanism, and with means provided for optionally, either preventing clutch packing engagement of the clutch mechanism under the normal influence of the speed responsive automatic means, or causing disengagement of the multi-clutch mechanism from its speed responsive automatic means clutch-packed engaged state. And, to the end of providing for preventing, or for causing disengagement of, clutch-packed engagement of the multi-clutch mechanism under the influence of the speed responsive automatic means, the present invention further contemplates the provision of a distinct optionally disengageable clutch unit of frictionally engaging elements forming a bottom pressure element to the multiple of speed responsive automatic engageable clutch units of the multi-clutch mechanism, with automatic but yielding means provided to normally close this distinct optionally disengageable clutch unit, and with means provided for forcing the yielding means to yield with consequent opening of this clutch. All such that the normal bottom pressure effectiveness of this optionally disengageable clutch unit to the multiple of speed responsive automatic clutch units is withdrawn such that all the speed responsive automatic clutch units of the multi-clutch mechanism are rendered non-packable into clutch engagement by the speed responsive means.

Still another object of the invention is, the provision of a multi-clutch mechanism combining a positive type centrifugal automatic clutch mechanism and a friction type spring-means-normally-engaged clutch mechanism both operating to complete driving connections of a given train of power transmitting members. The positive type centrifugal automatic clutch unit of which combination being preferably for cooperation with a planetary gear unit which would afford rotation of the centrifugal element of this clutch unit only upon the torque being reversed from that at which the load is propelled through such planetary gear unit. The normally engaged friction clutch mechanism of this combination being adapted to normally complete the driving connections of the train upon the positive type centrifugal clutch becoming engaged under the rotation of this reverse of torque. The friction type clutch mechanism forming a clutch mechanism adapted to be optionally opened to effect a break in the united planetary gear unit such that would permit the positive type centrifugal clutch, once engaged or united, to come to rest with its released associate element of the planetary gear train and thus disengage. Whereupon, the speed ratio of drive, in effect before the engagement of the positive type centrifugal clutch unit, would again come into play.

Other objects of the invention reside in the provision of a simplified multi-clutch mechanism structure wherein parts are minimized and wherein, more specifically, centrifugal members function as clutch engagement packing actuators and as devices timing secondary clutch engagements such that higher than ordinary speeds of rotation are attained before initiating said secondary clutch engagements.

The accompanying drawing is a vertical longi-

75 tudinal section taken through a multi-clutch mechanism constructed in accordance with the invention, and shows also a gearing which, is exemplary only of one form of associate power transmitting means, in conjunction with which the multi-clutch mechanism would cooperate advantageously.

As above set forth the invention is shown and described in the environment of an automotive vehicle. Accordingly, the fly-wheel of an internal combustion engine is shown at 10 to rotate with the end of an engine crank shaft 11. A driven power transmitting member is illustrated at 12 and adapted to be connected to the vehicle's driving wheels to propel same. The usual clutch shaft element of the drive is illustrated in a multiple of four concentric members comprising a low or first speed shaft 13, a second speed shaft 14, a third speed shaft 15 and a fourth speed (direct drive) shaft 16, all forming intermediate shafts with respect to their disposition relative to the driven shaft 12 and the engine crank shaft 11 which latter may be termed the driving member.

An exemplary multi-speed gearing which would cooperate with each of the multiple of clutch shafts 13, 14, 15 and 16 is shown in conjunction with the present multi-clutch invention, and such gearing with which the multi-clutch mechanism would cooperate advantageously, is illustrated as follows: A planet carrier 17 rotatable with the driven shaft 12, a planet gear cluster 18 mounted upon the planet carrier 17 and comprising integral large and small planet gears 19 and 20, a large sun gear 21 rotatable with the clutch shaft 14 and meshing with the smaller planet gear 20, a smaller sun gear 22 meshing with the larger planet gear 19 and to be driven from the clutch shaft 13, and an internal gear 23 forming a distinct pivotal element meshing with the large planet gear 19 constitutes one planetary gear unit operative to drive the driven shaft 12. A second planet carrier 24 is rotatable with the internal gear 23; a distinct planet gear element 25 is mounted upon the second planet carrier 24; a sun gear 26 is rotatable with the clutch shaft 15 and meshes with the second planet gear 25 and a second internal gear 27 forming a distinct pivotal element and meshing with the second planet gear 25 constitutes a second distinct planetary gear train. A transmission case 28 shown integral with a clutch housing 29 has integral portions 30 and 31 respectively forming stationary annulus elements to separate overrunning brake units 32 and 33. The overrunning brake unit 32 comprises the customary roller brake members 34 and the customary cams 35 formed on the hub portion 36 of the second internal gear 27 and operates to prevent rotation of this internal gear 27 backwards. While the overrunning brake unit 33 comprises the customary roller brake members 37 and the customary cams 38 formed on the hub portion 39 of the internal gear 23 and operates to prevent backwards rotation of this internal gear 23. The clutch shaft 13 is constructed separate of the sun gear 22. An overrunning clutch comprising, a driven annulus 40 integral with the sun gear 22 and the customary cams 41 formed on the periphery of the clutch shaft 13 and roller clutch members 42 forms a one-way drive means between the clutch shaft 13 and the sun gear 22. It will be seen that forward driving by the clutch shaft 13 first will cause forward one-way driving of the sun gear 22 through the medium of the over-

running clutch rollers 42, resulting in reverse rotation of the planet cluster 18, consequently causing the planet gear 19 to rotate in the internal gear 23 and by virtue of the latter being prevented from rotating backwards by the roller brake members 37 causes the planet carrier 18 and integral driven shaft 12 to be forward driven at reduced speed giving a first speed ratio.

It follows, that under drive taking place subsequently through the shaft 14 the smaller planet gear 20 will be caused to rotate reversely by the larger sun gear 21 with the result that the planet gear 19 will be rotated faster than heretofore. This will cause the smaller sun gear 22 to rotate faster than its individual driving clutch shaft 13 as permitted by the overrunning clutch rollers 42. In other words the supplantation of the drive of the sun gear 22 by the drive of the sun gear 21. The consequent faster rotation of the planet gear 19 will carry same around its gear track in the internal gear 23 at a higher speed and result in the planet carrier 18 and the integral drive shaft 12 being stepped up from first to second forward driven speed ratio.

Up to this time the planet carrier 24 has stood still with its integral internal gear 23 operating as a respective member under drive first from the clutch shaft 14 and then the clutch shaft 13. Upon the clutch shaft 15 being connected to rotate with the driving member 11 as a unit with the already connected clutch shafts 13 and 14 thereto, it will be seen that the planet gear 25 will rotate reversely and run around its gear track in the internal gear 27 because of the latter being prevented from rotating backwards by the brake rollers 34. This will result in the planet carrier 24 and its integral internal gear 23 being driven forwardly at reduced speed with the result that the individual gear track to the planet gear 19 will rotate forwardly carrying the planet gear 19 with it. Since the planet gear 19 is also under forward drive by the sun gear 21, the speed of the planet carrier 18 will obviously be stepped up as a result of the second planetary gear unit coming into driving play. The two planetary gear units thus set into collective gear train driving operation, as a result of the third clutch shaft 15 adding to the drive, changes the speed ratio of drive to the driven shaft 12 from that of second to third. If the fourth clutch shaft 16 were to be connected to rotate with the driving member 11, together with the other three clutch shafts 13, 14 and 15, and if then or thereafter the clutch shaft 16 and the internal gear 27 were to be connected to rotate together, it will be seen that the planetary gearing in its entirety comprising both distinct planetary gear units would become locked into a unity to rotate in mass forming a direct drive of all the clutch shafts 13, 14, 15 and 16 and the planetary gearing between the driving and driven shafts 11 and 12, giving the fourth speed ratio of drive to the driven shaft 12.

On the premise of this relationship between the four clutch shafts and the exemplary form of gearing shown, the present multi-clutch mechanism invention is described as follows:

A clutch shell or detachable part of the flywheel 10 is indicated at 43. Within and rotatable with but mounted for longitudinal movement relative to the flywheel 10 are multiple driving clutch plates 44, 45, 46, 47 and 48 enclosed at the front end by the disk portion of the flywheel 10 forming a final forward bottom pressure plate 49 and at the rearward end by a back portion 50 of the clutch shell 43 forming a base for master re-

tractive clutch springs 51. The most rearwardly of the driving clutch plates 48 serves as a rearward final bottom pressure plate.

A shoulder 52 in the clutch shell provides a suitable stop limiting the movement of the driving plate 46 and upon which the latter is adapted to rest normally. To the end of causing the plate 46 to normally rest against the shoulder 52, a spacer 53 is arranged in the clutch shell 43 to seat rearwardly against the driving clutch plate 47, and secondary retractive springs 54 are compressed between the plates 46 and spacer 53 such that the plate 46 normally but yieldingly rests against the shoulder 52 and such that, through the medium of the spacer 53, the plate 47 is constantly urged rearwardly toward the rearward final bottom pressure plate 48. In rotation with the fourth speed clutch shaft 16 is a driven clutch disk 55 disposed to be clutch engagingly packed between the driving plates 47 and 48. Since the master retractive springs 51 operate to constantly urge the plate 48 forwardly and since the secondary retractive springs 54 constantly operate to urge the plate 47 rearwardly, the fourth speed (high) driven disk 55 is normally clutch spring pressure-packed between the plates 47 and 48, giving a conventional normally but yieldingly engaged clutch effect. A stop indicated at 56 limits the movement of the spacer 53 and in turn the plate 47 such that, influenced by the springs 54, the plates 46 and 47 will normally rest at a fixed distance longitudinally apart.

So that the fourth speed driven clutch disk 55 may be unpacked, that is to say this clutch unit released, at the option of the driver, the customary clutch release fingers 57 acting upon studs 58 threaded into apertures provided in the rearward final bottom pressure plate 48 are provided, and the customary clutch release or throw-out bearing 59 for actuating the release fingers 57 is also provided to actuate the fingers 57 forwardly at their inner ends to pull the plate 48 rearwardly.

Since the fourth speed clutch shaft 16 is shown to normally be connected by means of the above described normally engaged but optionally disengageable friction clutch, and since to effect the fourth speed, that is to say complete the driving connections of the fourth speed, the internal gear 27 must be connected to rotate with the clutch shaft 16. The present invention contemplates the provision of a positive type centrifugal automatic distinct clutch unit preferably operating between the internal gear 27 and the clutch shaft 16. A desirable adaptation of a positive type centrifugal automatic clutch at this point would be one the centrifugal actuating means of which was carried by the internal gear 27. For, since the internal gear 27 normally stands still or at least normally rotates at a speed relative to the clutch shaft 16, and since the internal gear 27 is adapted to respond to a reverse of torque and accelerate up to or beyond the speed of the clutch shaft 16, this could advantageously provide that the centrifugal means would not function to engage the clutch and connect the clutch shaft 16 and internal gear 27 until the torque had been reversed and then not until the driving and driven parts, respectively, clutch shaft 16 and internal gear 27 had attained synchronous speeds. This therefore, would leave the third speed ratio of drive operable at any vehicle speed attained under acceleration at the option of the driver to permit automatic shift to fourth by momentarily decelerating the engine to promote the momentary reverse of torque required to accelerate the

internal gear 27 and centrifugal clutch actuating means responsive thereto. A suitable form of positive type centrifugal automatic clutch for this adaptation is indicated at *f* and comprises clutch teeth 60 on the fourth speed clutch shaft 16, a longitudinally shiftable clutch member 61 splined as indicated at 62 to the internal gear 27 and shiftable from its normal resting position (shown) forwardly until the splines in the bore of the shiftable clutch member 61 engage and mesh-overlap sufficiently in the driving clutch teeth 60. So that the clutch member 61 will normally rest retracted out of engagement with the shaft 16, retractive springs 63 are provided to urge a stud 64, the latter threaded into a flange portion 65 of the clutch member 61, and in turn the clutch member 61 rearwardly. The stud 64 passes through a flanged portion 66 of the internal gear member 27 and lends compression action to the spring 63 against a washer 67 limited (by any suitable means such as a pin through the stud behind the washer 67) in movement over the stud rearwardly. To actuate the clutch member 61 forwardly into engagement with the clutch teeth 60 of the shaft 16 upon the internal gear 27 being rotated up to a sufficient speed, a centrifugal weight element 68 is mounted on the internal gear member 27 so that a foot-portion 69 of the weight 68 will press forwardly against the flange-portion 65 of the clutch member 61 and overcome the normal influence of the spring element 63. Thus I have described a distinct clutch unit *f* of the multi-clutch mechanism which will remain disengaged until a reverse of the torque in the transmission initiates rotation of a certain member of the transmission otherwise designed and equipped to stand still.

The clutch unit, of which the normally engaged but optionally disengageable clutch element 55 is a component, and the torque reversal centrifugal positive type clutch unit *f* of which the shiftable dentated member 61 is a component, form a system cooperating with the pivotal element, and for completing the driving connections of, one speed ratio of drive effective planetary gear train of a planetary type gearing, such that the respective planetary gear train may be disconnected at will by releasing the friction clutch disk 55 to facilitate the pivotal element 27 of the respective associate planetary gear train reverting to its normally restrained state of rest with resultant automatic disengagement of the positive type centrifugal clutch member 61 from its driving member 16 under urge of the spring 63. Whereupon, the clutch disk 55 may be clutched again without influencing the transmission. One service of the normally engaged clutch unit of which the disk 55 is a component is to superimpose a control of the driving connection over the cooperating positive type centrifugal automatic clutch unit.

For individually connecting the other three clutch shafts 13, 14 and 15 to the driving member 11, respectively in the order named and respectively automatically in response to stepped predetermined speed of rotation attainments by the driving member 11, the invention further contemplates three separately engaging master centrifugal automatic clutch units respectively indicated at *a*, *b*, and *c*.

The rearwardly disposed normally spring-engaged clutch unit *d* completes the flywheel system of four distinct drive connecting clutch units, and due to its mass comprising spacer 53, plates 47 and 48 and disk 55 being normally packed for-

wardly against the stop 66 by the urge of the master springs 51, it operates as a back rest for all three of the centrifugal automatic clutch units *a*, *b*, *c*. This relationship of the normally engaged fourth clutch unit *d* to the three centrifugal automatic clutch units *a*, *b* and *c* is obtained in the first instance by virtue of the secondary spring 54 resting against the spacer 53 which latter in turn rests against the plate 47 which operates as a first bottom pressure plate to the clutch unit *d*. And in the second instance by virtue of the first bottom pressure plate 47 to the normally engaged clutch unit *d* also having a portion 70 operating as a rearwardly disposed bottom pressure plate to the centrifugal automatic clutch unit *c*.

The first engageable unit of the centrifugal automatic clutch units *a*, *b* and *c* is the unit *a*. This distinct clutch unit *a* comprises plate 44 operating as a forwardly disposed bottom pressure plate to the unit *a*, plate 45 operating as a pressure plate to engagingly clutch when thrust forwardly, a driven clutch disk 71 to unit *a*, rotatable with the first speed clutch shaft 13 and disposed and to be packed between the plates 44 and 45, plate 46 operating as a back plate to unit *a* and normally urged forwardly to rest against the shoulder 52 by the spring 54, and master centrifugal weights 72 having feet portions 73 wedged between the presser and back plates 45 and 46. So that the presser plate 45 of unit *a* will be normally retracted out of engagement with the disk 71, a bolt 74 is threaded into the plate 45, and it extends through the back plate 46 and is equipped with a retractive spring element 75 and washer 76 such that the spring will effect a constant rearward urge upon presser plate 45 by which the weight 72 is normally held in its ineffective state.

40 The forwardly first bottom pressure plate 44 of the first engaging centrifugal automatic clutch unit *a* has a portion 77 acting as a presser plate to the second engaging centrifugal automatic clutch unit *b*. The clutch unit *b* has an individual driven clutch disk 78 rotatable with the second speed clutch shaft 14 and disposed to be clutch-packed between the flywheel portion 49 and the presser plate portion 77 of the plate 44.

45 So that the combined bottom pressure plate 44 and presser plate 77 will first act as a bottom pressure plate to the first speed clutch unit *a* without acting as a presser plate to the second speed clutch unit *b* under initial pressure from the master centrifugal weights 72, the invention 50 contemplates further the provision of dead center linkage *e* between and normally operative to rigidly space the plate comprising portions 44 and 77 rearwardly away from the flywheel plate portion 49. By virtue of the linkage *e* (being 55 normally in a dead center state) the plate 44 is rendered resistant to extreme longitudinal pressure from the rear whereby the centrifugal weights 72 may thrust the presser plate 45 and in turn the disk 71 hard against the plate 44 and effect a high torque capacity clutching by the 60 first speed unit *a* of disk 71 without initially effecting any clutching tendency upon the second speed clutch unit *b*.

65 The invention further contemplates that the master centrifugal weights 72 will operate above a second speed of rotation attained by their carrying member to energize the clutch-packing of the second speed disk 78 against the flywheel portion 49 through the medium of the plate portions 44 and 77 at the expiration of a predetermined

mined interim following clutching of the first speed disk 71 under initial pressure from the centrifugal weights 72. To time this interim to correspond to the acceleration interval say between 500 R. P. M., at which it is desired that the engine take on the load in first speed, and say 2000 R. P. M., at which the engine has accelerated the vehicle to say 15 M. P. H., respectively, between desired engagements of first and second speed disks 71 and 78 under urge from the same centrifugal weights 72, the dead center toggle linkage *e* may be constructed and equipped as follows: Two links 79 and 80 are linked by pins 81, 82 and 83 and brackets 84 and 85 to make a dead center toggle in a horizontal (longitudinal) plane between the plate 44 and the flywheel portion 48, when urged radially inward at the center pin 82 and to rest against a stop indicated at 86. So that the center wrist of the linkage *e* concentrated around the center pin 82 will normally rest against the stop 86 such that the dead center toggle is normally in effect to rigidly space the plates 44 and 48, a centrifugal weight 87 is pivoted to the center wrist connection of the links 79 and 80 by the center pin 82, and a spring element, preferably comprising at least two springs 88 and 89 (spaced longitudinally side by side, as illustrated, so that it will be an influence to maintain the weight 87 upright), is provided and interposed radially between the weight 87 and the rim of the flywheel 10. It will be seen that the springs 88 and 89 (of sufficient tension) will operate to restrain the weight 87 from responding to the speed of rotation of the carrying member 10 (flywheel) until the hereinbefore-mentioned second predetermined speed of rotation by the driving member 11 and wheel 10 had been reached, at which time it is desired that the built up pressure of the weights 72 at this comparatively high speed and residing in the plate 44 be released to almost immediately thrust and pack the second speed disk 78 between the portion 77 of the plate 44 and the flywheel portion 48.

It will be seen that the tension and centrifugal coefficients, respectively, of the springs 88 and 89 and the weights 87 may be of such predetermined values that the centrifugal force will counteract the spring tension at almost any desired speed of rotation by the member 10. And that upon the centrifugal force of the weight 87 overcoming the tension of the springs 88 and 89, the center or wrist pin 82 will be carried radially outward causing the gradual collapse of the dead center-toggle-effect of links 79 and 80.

Since the master centrifugal weights 72 will first effect the engagement of the first speed clutch disk 71 by virtue of the plate 44 being temporarily prevented (by the dead center toggle linkage *e*) from moving forwardly under the thrust, the centrifugal force of the weights 72 will obviously build up (as the speed increases after the clutching of the disk 71) in the plate 44. So that, upon the independently centrifugally timed collapse of the linkage *e* out of its normal dead center toggle state, this built up master centrifugal force in plate 44 will almost immediately effect the clutching of the second speed clutch disk 78 to the flywheel 10. Thus I have described in considerable detail the first and second speed, or first two successively acting centrifugal automatic clutch units of the multi-clutch mechanism.

It is contemplated that the tension of springs 84 and 85 be such that the back plate 48 will not move rearwardly appreciably under the re-

action urge of the foot 78 of the centrifugal weight 72 until a speed of rotation of the member 10 has been attained which will be an appreciable step higher than that at which the linkage *e* was centrifugally caused to collapse out of its dead center toggle state and the resultant centrifugal engagement of the second speed clutch disk 78. This will provide that above a third predetermined speed of rotation attained by the member 10, the springs 84 or 85 will yield sufficiently to cause a certain backing up of the plate 48 which latter, up until now, has operated exclusively as a back plate taking the reaction pressure of the master centrifugal weights 72. The invention contemplates the use of this aforementioned third-predetermined speed attainment centrifugally accomplished yielding of springs 84 and 85 and resultant initial appreciable backward movement of the plate 48 to time, and effect a priming of, a third centrifugal-automatic clutch unit forming a normally non-rotating third speed clutch unit to be initially rotated.

While the present invention contemplates the use of centrifugally controlled dead center toggle linkage means to time the nonexcessive slip engagement of one unit of clutch mechanism adapted to one speed ratio of drive, it contemplates also the use of another centrifugal equipped clutching unit adapted to normally remain at a standstill until excited to initially rotate by a centrifugal means timer. Such normally-still centrifugal-automatic clutch unit affording that the centrifugal weight element may have a centrifugal coefficient relative to retractive spring tension much higher than ordinarily, and by this virtue provide a centrifugal automatic clutch unit which, once excited to rotate up to the speed of its driving associate member, will develop a high torque centrifugal engagement almost instantly, but with sufficient smoothness (absence of jerk in the resultant change of speed ratio) as to be most satisfactory.

To the end of providing a distinct centrifugal automatic clutch unit in the multi-clutch mechanism such as lastly above described, the present invention contemplates the clutch unit *c* comprising a pair of longitudinally relatively expandable driven clutch plates 90 and 91 related relatively expandable (with respect to each other), respectively, plate 90 toward the plate 48 and plate 91 toward the plate portion 78, whereby the driven plates 90 and 91 may be clutch packed between the respective associated driving clutch pair of plates 48 and 78. To complete the packing of this distinct clutch unit *c* to give a distinct driving connection function, the invention also contemplates a supplemental driven-clutch plate 92 disposed preferably between the driving plate 48 and the adjacent driven clutch plate 90 of the first-mentioned two driven clutch plates 90 and 91.

For identification, I term this last-referred-to distinct centrifugal automatic clutch unit *c* a free centrifugal clutch, because the centrifugal or speed responsive automatic actuating mechanism of this respective clutch unit is free to standstill while not sufficiently engaged frictionally by some associated member, to cause same to rotate, and because it is also normally independently revolvable of any other member.

To the end that the supplemental driven plate 92 operates as an ordinary driven clutch disk to an associate clutch shaft the invention contemplates that this plate be splined as usual and as

indicated at 83 to rotate with its associate clutch shaft 15. Preferably this driven clutch plate 82 is equipped with clutch facing on either side as indicated at 84 and 84a. To render the pair of longitudinally clutch expandable driven clutch plates 80 and 81 normally independently revolvable and free to standstill until frictionally-engaged by some associate member, the plate 80 preferably is provided with an axial bore being bearing-bushed as indicated at 85 such that the plate 80 revolvably fits upon the journal-like periphery of a hub portion 86 of the supplemental driven plate 82. A suitable material for this bearing bushing 85 would be bronze with a high graphite content to render it self lubricating for its very limited relative movement bearing duty.

To the end that the normally rotatably free driven clutch plates 80 and 81 of clutch unit c may normally rest in a state at a minimum distance apart such that it will hold the clutch unit c completely disengaged, the invention contemplates a rearward abutment 97 carried in a fixed position by the hub portion 86 of the plate 82 and a spring 98 compressed between the plate 80 and the abutment 97 so that the supplemental driven plate 82 which is rotatable with the shaft 15 will frictionally-press against the otherwise rotatable free plate 80 sufficiently to render a slight brake effect upon the free plate 80 and that a standstill state of the clutch shaft 15 and the supplemental plate 82 will predominate over rotation of associate driving elements thereto, such as driving friction plates 46 and 70. This brake tension provision upon the distinct centrifugal automatic clutch unit c is designed to maintain the normally free clutch plates 80 and 81 in relationship rotatively exclusively with its associate clutch shaft (individual carrying member) until the speed predetermined timed moment for response of the distinct centrifugal clutch mechanism unit c to the driving member speed and at which moment the plate 46 acting as a presser plate to this particular clutch unit c will have been thrust rearwardly against the tension of springs 54 or 51 into effective driving engagement with the supplementary driven clutch plate 82, resulting in turn, in the normally free driven plate 81 being thrust rearwardly into engagement with the plate 70. At this point it will be seen that the normally engaged distinct clutch unit comprising plates 47 and 48 and disk 55, clutch packed between the spacer 53 and stop element 56 on one side and the springs 51 on the other side, will operate as the bottom pressure element to the engaging distinct clutch unit comprising the driven plate assembly of plates 82, 80 and 81 and the presser plate 46 thereto. Further, at this point it will be seen that sufficient retraction (by actuating the fingers 57) of the bottom pressure plate 48 will operate to spread the distinct bottom friction plate 70 to the clutch unit c away from the presser plate 46, to the same clutch unit c, such that the clutch unit c could not expand longitudinally sufficiently to effect clutching of unit c. The optional disengagement of the fourth speed clutch unit d is seen therefore to control the engageability of the third speed clutch unit c to such an extent that the latter may be either prevented from automatically clutching at its predetermined speed normally controlled time or caused to disengage at any time after it has automatically engaged. Likewise, it will be seen that the optional disengagement of the fourth speed clutch unit d may be sufficient to allow retraction of the back plate 46 75

to the centrifugal weights 12 sufficiently to disengage the first speed driven disk 71 of clutch unit a and in turn allow the plate 44 and portion 17 thereof to retract rearwardly sufficiently to release 5 the second speed driven clutch disk 78. It is seen therefore that in the multi-clutch mechanism I have provided optional disengagement of a conventionally (normally) engaged ordinary friction clutch d (respectively designed in this adaptation to function contributory to connecting a fourth speed) which, besides the desired primary results obtained by its individual disengagement, will effect disengagement or prevent engagement of a plurality of other distinct clutch units a, b 10 and c respectively associated with other speed ratios of power transmission.

Returning to the detail of the clutch unit c. To the end that the plates 80 and 81 will normally remain longitudinally at a minimum distance apart, the invention contemplates means comprising a stud 99 threaded into an aperture provided in the plate 80, passing through the plate 81 giving a slip fit of the latter thereon and carrying a spring 100 compressed by suitable means against the plate 81 such that the plates 80 and 81 will be constantly but yieldingly urged toward each other longitudinally.

To the end that the normally still plates 80 and 81 may be thrust farther apart longitudinally such that the driven plate 81 will be thrust hard against the driving plate 70 and the supplemental driven plate 82 will be thrust hard against the driving plate 46, immediately and with minimum slip even under maximum torque, following 30 the priming frictional engagement of the plate 46 with the driven plate 82, the invention further contemplates the provision of the following means. Individual centrifugal weights 101 are mounted by feet portions 102 wedged operatively between the normally still plates 80 and 81 and designed to thrust these plates apart immediately at a high pressure coefficient relative to comparatively low speed of rotation. To obtain this high pressure coefficient from the centrifugal weights 101 at low speed of rotation such that maximum torque capacity engagement of the clutch unit c will result immediately from low pressure priming-to-rotate engagement of the presser plate 46 with the normally still assembly of driven plates 82, 80 and 81, advantage is taken of the virtue of this assembly of driven clutch plates of clutch unit c normally standing still until engaged by the plate 46. The requirement hence of the retractive or clutch disengaging spring element 100 distinct to clutch unit c, to straighten the centrifugal weights 101 into their normal non-speed responsive positions and to retract the plates 80 and 81 into their aforementioned minimum positions apart longitudinally while at rest would be slight. This requires that the centrifugal weights 101 be of unusually high centrifugal value relative to their retractive spring element 100. It also requires that the rate of centrifugal acceleration distinct to effecting maximum torque engagement of the clutch unit c will be unusually high.

So that the relative-movement end of the spring 98 will not be required to work against the respective abutment of the same, preferably the abutment 97 is made to consist of at least two parts for relative rotative movement therebetween. A suitable bearing provision of these two parts would be to provide the outer part of steel and the other part, being that between the outer

part and the spring end, of graphite impregnated bronze.

It will be noted that the design of gearing illustrated, exemplary of that which would coordinate advantageously with the multi-clutch mechanism, and the latter while comprising five distinct clutching units giving four speed ratios of driving connections and affording directly optional de-clutching of four of the five distinct clutching units and facilitating indirectly optional de-clutching of the fifth distinct clutching (positive type) unit, still gives a mechanism the entirety of which gearing, shafting and clutch mechanism may rotate as a unit when in the highest speed ratio of drive state of connection.

Operation of the invention follows:

With the engine (driving member 10 and 11) idling under, for example, 500 R. P. M., the pressure of the springs 88 and 89 is greater than the centrifugal force of the weights 87 thus establishing a dead center relationship of the toggle linkage e and resulting in the plate 44 and portion 71 being locked longitudinally with, but at a maximum distance away from, the bottom pressure portion 48 of the flywheel 10. This renders the second speed clutch unit b open; and with the engine (driving member 10 and 11) idling under 500 R. P. M., the value of the retractive springs 75 is greater than the centrifugal force of the weights 72, resulting in the plate 45 being held at a maximum distance from the plate 44. This renders the first speed clutch unit a open; and with the engine (driving member 10 and 11) idling under 500 R. P. M., the value of the springs 54 and 51 is greater than the reaction force of the centrifugal weights 72 against their back plate 46, thus preventing a driving engagement of the plate 46 with the plate 92. This leaves the free third speed centrifugal automatic clutch unit c unmolested; and, by virtue of the driving clutch units a, b and c remaining disengaged, the planetary gearing including the internal gear 21 may remain at rest. This assures that the positive type centrifugal automatic clutch unit f will stand disengaged. The single normally engaged clutch unit being the fourth speed completing clutch unit d. Therefore, clutch shafts 13, 14 and 15 stand still while the driving member 10 idles under 500 R. P. M., and the clutch shaft 16 rotates (through the medium of the engaged clutch unit d) with the driving member 10.

Assuming a desired performance of starting the vehicle (load on driven shaft 12) from a standstill and accelerating through different speeds to ultimately reach a top speed ratio, the engine (driving member 10 and 11) is accelerated. Passing above the 500 R. P. M. (exemplary first predetermined speed of driving member) the weights 72 overcome the springs 75 and thrust the plate 45 forwardly. The toggle e still prevents the plate 44 from backing away from any thrust from the rear. Hence the first speed driven clutch disk 71 becomes automatically clutch packed between the plates 44 and 45 by the first predetermined speed attainment of the driving member 10. Thus resultant connection of the clutch shaft 13 to rotate with the engine shaft 11 promotes the one-way drive of the first speed sun gear 22 through the medium of the roller clutch members 42. Subsequently, gears 19 and 23 back the torque of this drive up against the roller brake members 37 in the stationary annulus 33 and cause the planet carrier 17 and the integral driven shaft 12 to rotate forwardly 75

at the lowest ratio of speed relative to that of the driving member 11.

For example, at a vehicle speed of 10 M. P. H. under drive of this first gear (which latter if of 5 3 to 1 ratio would find the engine rotating at say 1500 R. P. M.), would cause the centrifugal weights 87 to overcome the springs 88 and 89. A result would be the collapse of the dead center toggle effect of linkage e, permitting the centrifugal force of the weights 72, built up in the packed plates 45, 71 and 44 between the 500 and 1500 R. P. M. attained by the driving member 11, to be gradually but quickly exerted in the way of thrusting the portion 71 of the plate 44 forwardly as the linkage e gave way under the somewhat gradual yielding of the springs 88 and 89. This resulting in the second speed driven disk 78 becoming packed between the portion 49 of the flywheel 10 and the portion 71 of the plate 20 44. The second speed clutch shaft 14 now rotating with the driving member 11 supplants the first speed drive of the sun gear 22 with the second speed drive of the sun gear 21. The sun gear 22 overrunning its clutch shaft 13, the torque 25 of this second speed drive backing through gears 19 and 27 against the roller brake members and annulus 37 and 33 with consequent driving of the planet carrier 17 and integral driven shaft 12 at second gear reduced speed relative to that 30 of the driving member 11.

For example, at a vehicle speed attainment of 20 M. P. H. under the drive of the second speed clutch b and shaft 14 at a reduced speed ratio (for example of 2 to 1 at which 20 M. P. H. the engine would reach an R. P. M. of about 2000 R. P. M.), the force of the centrifugal weights 72 (now positively resisted on the front by the clutch packed assembly of plates 45, 71, 44 and 78 against the portion 49 of the flywheel 10) 35 40 would have overcome either the springs 54 or the springs 51, or both, sufficiently to have incurred the centrifugal-means-forcing of the reaction plate 46 to the centrifugal weights 72 rearwardly (as a presser plate) into engagement with the driven clutch plate 92. By this engagement, the centrifugally actuated plate 46 becomes an exciter to initiate rotation of the normally still assembly of driven plates 92, 90 and 91. Since this assembly (clutch c) has its own master 45 speed responsive actuating means 101; and this assembly (clutch c) is not rotated until the driving member thereof has attained a speed of substantially 2000 R. P. M. (corresponding to 20 M. P. H. vehicle speed attainment in second 50 gear); and since the assembly of driven clutch elements of this clutch c and their individual speed responsive means 101 will be urged by engagement by the driving clutch plate 46 to accelerate at once from a standstill to the aforesaid 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

By virtue of the planetary gear unit comprising gears 21, 25 and 26 remaining inactive (standing still as a unit) while the transmission is oper-

ating in first or second gear, respectively, under drive of either shaft 13 or shaft 14, which inactive state of gears 21, 25 and 26 is the result of the distinct planet carrier 24 thereto being integral with the pivotal element 23 of either the first or second speed gear trains hereinbefore identified, the third speed clutch shaft 15 and the driven assembly of plates 92, 90 and 91 and distinct centrifugal weights 101 all are caused to stand still until excited to rotate as hereinbefore stated by priming engagement of the driving plate 46 therewith.

The invention contemplates the further advantage from the novel multi-clutch provision, and in connection with a gearing such as the exemplary design shown, in that the third speed ratio of drive incurred by the accumulative engagement of the novel quick-acting centrifugal automatic clutch *c* supplementing the previously engaged clutch unit *b*, with resultant taking of the load (at third speed ratio from the second speed ratio) by the two planetary gear trains in series, will have the effect of placing but one half the load of the third speed on each of the two clutch units *b* and *c*. The operation of the two planetary gear trains in series to give the third speed ratio is the result of the engaged clutch unit *c* causing the sun gear 26 to initiate its drive of the planet gears 25 which latter, running in the internal gear 27 respectively held from rotating backwards by the roller brake members 34 and stationary annulus 32, impels the planet carrier 24 thereto to rotate at reduced speed in a forwardly direction and carry the internal gear 23 of the second planetary gear train with it. Whereupon, the normal (second speed ratio) drive by the previously engaged clutch unit *b* and shaft 14 and sun gear 21 and planet gears 19 to the planet carrier 17, is stepped up to that of a third speed ratio of speed reducing drive of the driven shaft 12. In contemplating this dual clutch and dual planetary gear train drive coordinating to give a change of speed ratio drive, especially a third speed ratio to supplant a second speed ratio, it is calculated that the high engine torque developed by the time such a speed change was advantageous in the process of load acceleration, would advantageously be served by two individually centrifugally served automatic clutches, such as the coordinate of a plurality of planetary gear trains in series to give a certain speed ratio of drive would cooperate with.

On the same premise of high engine torque prevailing at comparatively high vehicle speed attainments, the present invention contemplates and provides for bringing the fourth (top) speed ratio of drive into effect by the engagement of a distinct clutch unit co-related with preceding clutches engaged to the end that the load of the fourth speed ratio may be carried also by a multiple of individually energized clutch units. To this end, and also that the third speed may be maintained for acceleration to any desired vehicle speed attainment at the will of the driver, the invention contemplates the provision of the positive type centrifugal automatic clutch unit *f* which may be coordinated with a pivotal element of an internal gear train such that a torque-reversal control may be provided by the driver; in novel clutch co-working combination with either the normally engaged but optionally disengageable clutch unit *d*; whereby the positive centrifugal clutch *f* may be optionally facilitated to disengage at the will of the driver,

or in novel coordination with other of the individually energized clutch units of the multi-clutch mechanism such that it may be harnessed to the planetary gear trains in series whereby the load may be divided between the plurality of clutch units including the positive type unit *f*.

Therefore, at any vehicle speed attainment above, for example, 20 M. P. H. (at which the exemplary transmission will automatically normally come into play at third speed ratio drive), the driver may, by momentarily decelerating the engine, cause the fourth speed (direct drive by the exemplary transmission gearing) to come into play and supplant the third speed ratio. In detail, by momentarily decelerating the engine, the sun gears 21, 22 and 26 all being operatively connected to the driving member (engine shaft) 11, will have the immediate effect of accelerating the planet gears 19 and 25, respectively, to run around their decelerating sun gears 21 and 26, thus accelerating their respective internal gears 23 and 27 until the centrifugal weight element 68 carried by the internal gear 27 attains sufficient force and until the speeds of the clutch shaft 16 and internal gear 27 are substantially synchronous, at which moment the weight element 68 will actuate the positive clutch member 61 forwardly into clutch tooth mesh with the shaft 16. The entire exemplary planetary type gearing and multi-clutch assembly thus becomes locked into a rotating unity, giving a direct drive (fourth) positive connection between the driving and driven members 11 and 12.

It is a matter of common appreciation that ability, once in top speed gear, to easily revert the transmission to the next-in-ratio lower speed gear, would be very advantageous. To this end, the provision of the optionally disengageable friction type clutch unit *d* suffices. For at will, after the positive type centrifugal automatic clutch *f* has become engaged, the driver may momentarily cause the clutch unit *d* to disengage, thus loosening the shaft 16 and connected internal gear 27 from the driving member 11, whereby the internal gear 27 may decelerate below a speed of rotation at which the centrifugal weight element 68 will be overcome by the springs 63, with the result that the clutch member 61 will be shifted rearwardly out of engagement with the shaft 16. Whereupon, the clutch unit *d* may be allowed to engage again. The exemplary planetary gearing being thus reverted from one speed ratio downward to another relatively lower speed ratio.

Thus it will be seen that I have provided a novel, rugged and useful multi-clutch mechanism particularly advantageous for use in motor vehicles and capable of improved performance in connection with rendering automatic speed change control over multi-speed power transmissions.

It will be understood that various changes may be made without departing from the spirit of the invention as defined in the appending claims. I do not want to be limited to the examples and details described in the specification or shown in the drawing, as many variations will occur to those skilled in the art.

70 I claim:

1. In clutch mechanism, a revolvable clutch carrying power transmitting member, a bottom friction face portion of said carrying member, a presser friction clutch member rotatable with said carrying member, a coaxial engageable friction

element between said bottom and presser members, linkage carried by said carrying member, arranged between said bottom and presser members and adjustable therebetween in substantially a dead center toggle effect for firmly spacing said presser member away from said bottom member whereby said engageable friction element will be free to turn relative to said bottom and presser members, resilient means tending to adjust said linkage in said dead center toggle effect, said linkage having proportions and operable constituency whereby centrifugal force when said carrying member is rotated sufficiently will concentrate at a point operable to overcome the influence of said resilient means and centrifugally actuate said linkage out of said dead center toggle effect i. e., a state of collapse permitting said presser member to be actuated toward said bottom member to accomplish packing of said engageable element therebetween, and means including main centrifugally operable means carried in rotation with said carrying member operable to initiate urge upon said presser member beginning in response to comparatively slow speed rotation of said carrying member and to gradually increase the force of said urge in accordance with increasing speed of rotation of said carrying member such that when said collapse of said linkage from said dead center effect takes place a sufficient main centrifugally actuating force will be present in said presser member to accomplish substantially instant packing of said engageable friction element under torque at least so as to preclude an appreciable slip period between the frictionally-engaging elements, said linkage of itself forming a subcentrifugally operable means to time a permissible centrifugally actuated clutch engagement so that main centrifugally operable means to that end will not gradually transmit response to gradually increasing speed of rotation to the named frictionally-engaging members.

2. The mechanism described in claim 1, together with a primary presser member rotatable with said carrying member and directly acted upon by said main centrifugally operable means with retractive means including springs for holding said primary presser member from yielding appreciably to urge from said main centrifugally operable means until a predetermined speed of said comparatively low speed of said carrying member has been attained, and a first engageable friction element to turn relative to both said carrying member and the first-mentioned engageable friction element and disposed between said first-mentioned presser member and said primary presser member, wherein said first-mentioned presser member first operably constitutes a bottom friction member to said first engageable friction element, and wherein an engaged relation of said primary presser member and said first engageable friction element and said first operable bottom friction member under pressure from said main centrifugally operable means constitutes a presser body for subsequently packing said first-mentioned engageable friction element against said bottom friction face when said collapse of said linkage occurs.

3. In a clutch mechanism, two friction clutch members to rotate together normally to be spaced apart sufficiently to accommodate an engageable friction element being disposed freely rotatable relative therebetween and at least one of said two members adapted to be urged to move toward the other of said two members to lessen

their normal spacing whereby an engageable friction element therebetween would become clutch packed, dead center toggle linkage for adjustment in a dead center alignment when so adjusted forming means for effecting said normal spacing of said two members including a wrist of said linkage mounted on one and another wrist of said linkage mounted on the other of said two members and an intermediate wrist, means including a spring element concentrating an urge upon said intermediate wrist forming means for automatically adjusting said linkage in dead center alignment, and sufficient weight suspended around said intermediate wrist operable to concentrate sufficient centrifugal force therearound when said two members have attained a predetermined speed of rotation to overcome the influence of said springs and actuate said intermediate wrist out of said dead center alignment whereby a lessening of said normal spacing of said two members will be permitted, and means for, and adapted to have sufficient force at that time to immediately accomplish, said lessening of said normal spacing of said two members to a required degree for non-slip clutch packing of an engageable friction clutch element therebetween.

4. In a centrifugal friction clutch mechanism, the combination of a system of centrifugally operable means for engaging the clutch, a timer system of centrifugally operable means for holding the clutch elements against being actuated toward engagement by said engaging centrifugal system until the latter has passed through a sufficient increasing speed of carried rotation above that at which its centrifugal coefficient would overbalance its retractive spring influence and has thereby accumulated sufficient centrifugal pressure to substantially immediately hold the clutch against slip under the torque once engagement is initiated, a system of retractive springs for opposing the clutch engaging centrifugal action having a co-efficient to that end only effective to a peak idling speed of rotation, and a system of retractive springs opposing the timer system of centrifugal action having a co-efficient to that end effective to a considerably higher speed of rotation being that at which the clutch engaging centrifugal means will have accumulated said sufficient pressure to substantially immediately engage and hold the clutch.

5. In a centrifugal friction clutch, a bottom pressure friction member, a back plate, a presser plate adjacent said back plate and an intermediate plate between said bottom member and said presser plate, all rotatable together forming a multi-clutching coordination; two coaxial engageable friction clutch elements independently revolvable with respect to each other and to the named elements of said clutching coordination one disposed between said presser and intermediate plates the other between said intermediate plate and said bottom member; retractive means including springs urging said presser plate toward said back plate, clutch actuating centrifugally operable means operatively between said presser and back plates for actuating said presser plate away from said back plate when a first predetermined speed of rotation has been attained by said clutching coordination; retractive means operatively between said intermediate plate and said bottom member including springs effective to prevent movement of said intermediate plate towards said bottom member until a second, and appreciably stepped speed of rotation over said

first predetermined speed, has been attained by said clutch coordination; and means including masses acting against the springs respectively of the retractive means positioned aforesaid between said intermediate plate and said bottom member, forming masses centrifugally operable when said second predetermined speed of rotation has been reached to cause collapse of the respective retractive means thereby to release said intermediate plate movable towards said bottom member, an engaged unity comprising said presser plate and said intermediate plate clutching the interposed one of said engageable friction elements therebetween under pressure from said clutch actuating centrifugally operable means during the interim between said first and said second predetermined speed of rotation attainments forming an accumulatively built up pressure mass for movement towards said bottom member when said retractive means therebetween is collapsed centrifugally and for consequent clutching of the other of said engageable friction elements therebetween.

6. In a centrifugal clutch mechanism, a two stage engaging clutch unit comprising two independently revolvable friction clutch elements, a revolvable unit of clutching elements spacing said two engageable elements for spaced engagement with respect to stepped predetermined speeds of rotation being attained by said clutching unit of elements, a master system of centrifugally operable means for energizing engagement of the first of said two engageable elements when the first of said stepped predetermined speed of rotation has been attained and for latter energizing engagement of the other of said two engageable elements when the second of said stepped predetermined speeds of rotation has been attained, means including springs acting thereon for preventing response of the clutching elements movably towards accomplishing engagement of the second of said two engageable elements under urge from said master centrifugally operable means to that end following their effected engagement of the first of said two engageable elements, and independently centrifugally operable means operable when the second of said stepped predetermined speeds of rotation has been reached to release said preventing means suddenly for the until then restrained pressure of said master system of centrifugally operable means operating through their first effected clutching function to suddenly accomplish full torque holding clutch packing of the second of said two engageable elements.

7. In a friction clutch mechanism, the combination of a main spring and centrifugal weight coordination carried by the clutching division of the mechanism in which the spring tension and centrifugal forces balance when the carrying clutching division has attained a comparatively low first predetermined speed of rotation and wherein if not restrained therebeyond the centrifugal forces would tend to actuate the clutching division towards engagement such that clutch engagement would initially begin and progress under gradually increasing pressure in accordance with gradually increasing speed of rotation by said clutching division and accordingly allow a gradually diminishing clutch slip period under torque; and a coordination of other spring and centrifugal weight means spring operable, until a second and appreciably greater predetermined speed of rotation is attained by said clutching division of the mechanism, to prevent said clutch

engagement, under centrifugal urge from said main coordination of spring and centrifugal weights, from initially beginning and progressing under gradually increasing pressure in accordance with gradually increasing speed as aforesaid, and centrifugally operable when said greater predetermined speed of rotation is attained to release the clutching elements for substantially instantaneous engagement by the centrifugal forces of said main coordination up to a clutch holding coefficient under torque.

8. In a friction clutch mechanism, a multi-clutching embodiment comprising, in combination, a first unit of engageable driving and driven friction clutch elements and a second unit of engageable driving and driven friction clutch elements; first centrifugally operable means for gradually exerting increasing pressure for a consequent gradually increasing clutching coefficient in said first unit only in accordance with gradually increasing speed of rotation by the clutching embodiment from a comparatively low first predetermined speed of rotation up to a speed at which the centrifugal force will be sufficient to hold said first unit non-slip under full torque; a first system of springs yielding to said centrifugally operable means at said comparatively low first predetermined speed of rotation, means including a second system of springs for holding said second unit of engageable clutch elements open and operable in their open state as a non-yielding bottom friction element to said first unit while the latter are being gradually centrifugally engaged with increasing speed of rotation upwards from said first attained predetermined speed; and second centrifugally operable means, for overcoming said second system of springs thereby to loosen said second unit of engageable clutch elements actuatable to be engaged by pressure from said first centrifugally operable means adapted to reach said second unit of engageable clutch elements through the engaged state of said first unit, operable when a second predetermined speed of rotation has been attained and at which said first centrifugally operable means will be exerting a sufficient pressure in the engaged body of said first clutching unit to substantially instantaneously effect engagement of said second unit under full torque without appreciable slip period in said second clutch unit.

9. Mechanism as in claim 8 and wherein said second centrifugally operable means, following its operation loosening said second unit of clutch elements actuatable to be engaged under pressure from said first centrifugally operable means, with further increasing speed of rotation tends to energize engagement of said second unit supplementively over that tendency on the part of said first centrifugally operable means.

10. In a clutch mechanism, the combination with a driving member and a plurality of concentric driven members coaxial with said driving member, of an individual engageable friction clutch element rotatable with each of said concentric members, driving clutch elements rotatable with said driving member and spacing said engageable elements respectively that are rotatable with different of said concentric members into a multiple of separate clutching units, individual means including springs for separately disengaging each of said multiple of separate clutching units, centrifugally operable means for effecting engagement of first one and later another of said separate clutching units, and other centrifugally operable means solely for releasing

certain of said separate clutching units from their respective spring means held disengaged states whereby they may be actuated into engagement by said first-named centrifugally operable means.

11. Mechanism as in claim 10 and wherein said other centrifugally operable means comprises linkage for actuation into a dead center toggle effect by the spring means associated with the respective of the multiple of separate clutching units with which said other centrifugally operable means are also associated by said dead center toggle preventing engagement of the respective separate clutching unit, said linkage centrifugally operable to overcome said springs of the respective separate clutching unit and collapse out of said dead center effect thereby to permit said first-named centrifugally operable means operating to engage the respective separate clutching unit.

12. In a friction clutch mechanism, the combination of two clutching units of frictionally-engaging elements having first centrifugally operable means for energizing engagement of both and having combined spring and second centrifugally operable mechanism for spring predominance below a predetermined speed of rotation to hold the elements of one of said two clutching units non-actuable towards engagement under urge from their said first centrifugally operable means for engaging same and centrifugally operable above said predetermined speed of rotation to overrule said spring actuation and release the elements of said one of said two clutching units from said non-actuable state whereby they may be actuated into engagement under urge of their said first centrifugally operable means for effecting engagement of same.

13. In a multi-clutch mechanism which includes two units of frictionally-engaging clutch elements respectively adapted for separate and spaced engagement with respect to an appreciable differential between two predetermined speeds of rotation being attained, the combination of individual spring actuated means for disengaging each of said two units one up to a first predetermined speed of rotation being attained in the mechanism the other up to an appreciably greater second predetermined speed of rotation being attained in the mechanism, centrifugally operable means solely for actuating clutch engagement arranged operable first to effect engagement of said one of said two clutch units when said first predetermined speed of rotation has been attained and adapted to cumulatively effect engagement of said other of said two clutch units when said second predetermined speed of rotation has been attained, and other centrifugally operable means associated solely with said other of said two clutch units and therewith forming means solely for actuating said spring actuated means thereof out of its position, in which it effected disengagement of the respective clutch unit, when said second predetermined speed of rotation has been attained whereby said centrifugally operable means aforesaid solely for actuating clutch engagement may thereupon actuate said other clutch into engagement accumulatively over engagement of said one clutch unit.

14. A centrifugally operated friction clutch unit having a first system of centrifugally operable weights carried by one of its driving and driven members for urging engagement upon

the clutch through a considerable range of rotation speed, having means including springs spacing the clutching elements apart unmovable by said urge from said first centrifugal weights, and having a second system of centrifugally operable weights operable to overpower said springs and cancel their spacing influence between the clutching elements when a sufficiently high speed of rotation has been reached at which said first system of weights will have attained sufficient centrifugal force to substantially instantaneously accomplish the clutch engagement when under full torque without appreciable clutch slip.

15. Mechanism as in claim 14 and wherein said second system of centrifugally operable weights constitute secondary means centrifugally operable to energize engagement of the same clutching unit supplementively to the influence of said first system of centrifugally operable weights to the same end operating thereon but only after overpowering said springs at said sufficiently high speed of rotation for said first system of weights to substantially simultaneously accomplish full torque holding engagement of said clutch unit.

16. A centrifugally engaged friction clutch unit having a first system of centrifugally operable weights for urging engagement upon said clutch unit from a low speed of rotation upward throughout the rotation range and an independently operating coordination of spring and second centrifugally operable weights forming means for preventing responsive movements in said clutch unit towards engagement under said urge of said first system of weights until an appreciably greater speed of rotation has been attained whereupon said second centrifugally operable weights form means operable both to overcome the influence of said springs thereby to release the elements of said clutch unit to respond to said urge from said first system of weights and to supplement said urge with the urge of their own centrifugal forces to the common end of energizing engagement of said clutch unit.

17. In a centrifugally operated friction clutch mechanism, a given clutching unit having two independently operating systems of centrifugally operable weights for energizing engagement of the respective clutching unit one provided with resilient retractive means allowing the one system of weights to begin their clutch engaging actuating urge upon the respective clutching unit at a predetermined low speed of rotation the other provided with resilient means allowing it to begin its clutch engaging actuating urge upon the respective clutching unit only when an appreciably greater predetermined speed of rotation has been attained, the latter of the two systems of weights forming mechanism actuated by its own resilient retractive means into a position firmly blocking the clutching elements apart so they can not yield to urge from said one system of weights until said other system of weights have responded to speed at the point of said appreciably higher predetermined speed of rotation being reached.

18. In a centrifugally operated friction clutch mechanism, centrifugal weights normally positioned spacing the engaging elements of the clutch apart in an open clutch state, resilient means capable up to a predetermined speed of rotation to hold said weights in said spacing position, and other centrifugal weights adapted to have sufficient centrifugal force when said predetermined speed of rotation is reached to substantially instantaneously actuate said clutching

elements up to a full torque holding clutch gripping coefficient thus to obviate a prolonged slip period in connection with friction clutch engagement under torque.

19. In a centrifugally operated friction clutch having a bottom friction plate and a presser friction plate the latter adapted to be moved axially towards said bottom plate to effect clutching function within the clutch, the combination of a pushing centrifugally operable system of weights operatively behind said presser plate for thrusting same towards said bottom plate, and a system of pulling centrifugally operable weights operatively interconnecting said bottom and presser plates for pulling the latter towards said bottom plate.

20. The mechanism described in claim 19, together with a separate system of resilient retractive means for overcoming the pulling action of said system of weights, aforesaid having that character of action, until a predetermined speed of rotation has been attained, and a separate system of resilient retractive means for overcoming the pushing action of said system of weights, aforesaid having that character of action, until a predetermined speed of rotation has been attained.

21. The mechanism claimed in claim 19, wherein in said pushing system of weights are operable to engage one clutching unit and thereupon urge the engagement of a second clutching unit, and wherein said pulling system of weights are operable to release the elements of the second clutching unit to yield engagingly to said urge from said pushing system of weights, said pulling system of weights operable thereafter to supplement the urge by said pushing system of weights to the common end of energizing engagement of the second clutching unit.

22. In a centrifugally operated friction clutch mechanism, between a driving power transmitting member and a coaxial driven power transmitting mechanism, the combination of a contracting full complemented centrifugally operable clutching unit carried in rotation with said driving member, an expanding full complemented centrifugally operable clutching unit mounted rotatable independently of said driving member and disposed to be clutch packed between the clutching elements of said contracting clutching unit, and a friction clutch element mounted in an engageable position to turn with said driven member disposed as an intermediary between elements of both named clutching units so as to be clutch packed under centrifugal pressure from both named centrifugally operable clutching units.

23. In a centrifugally operated friction clutch mechanism, between a driving power transmitting member and a coaxial driven power transmitting member, a clutching unit for connecting said driving and driven members to rotate together comprising, in combination, a priming centrifugally operable clutching element carried in rotation with said driving member and having its own actuating centrifugal weights, a booster centrifugally operable clutching element mounted rotatable independently of said driving member and having its own actuating centrifugal weights, an engageable friction clutch element mounted in connection to turn with said driven member, said priming centrifugally operable clutching unit forming a clutching unit for exciting said booster centrifugally operable clutching unit to rotate up to the speed of said driving

member, said booster centrifugally operable clutching unit forming a secondary centrifugally actuating clutching unit to supplement the pressure of centrifugal forces operating in said priming clutching unit, and said priming and said booster centrifugally operable clutching units when both operating forming double pressure centrifugal energizing elements for clutch packing said engageable friction clutch element to rotate with said driving member.

24. In a centrifugally operated friction clutch mechanism between a driving power transmitting member and a driven power transmitting member, the combination of an exciter driving clutching system rotatable with said driving member and having its own centrifugal actuating means responsive to the speed of said driving member, and an excitable driven clutching system mounted rotatable independently of, but associated with, said exciter clutching system and having its own centrifugal actuating means carried in rotation therewith, the combined actions of said exciter and excitable clutching systems forming a clutch unit under double centrifugally operable systems for coupling said driven member to rotate with said driving member.

25. In multi-clutch mechanism positioned at different interruptions in a circuit of connections for transmitting drive when closed, the combination of a positive clutch unit for connecting one pair of members of said circuit engageable only when its two members are operating in substantial synchronism and having centrifugally operated means for moving one of the clutch members into engaged position; and a friction clutch unit for connecting another pair of members of said circuit, having resilient means normally but yieldingly engaging same and having means for its disengagement at will forming flexible coupling means in said circuit for opening and closing the latter without molesting said positive centrifugally engaged clutch unit.

26. Multi-clutch mechanism, differentially associated with change speed power transmitting mechanism for automatically changing the latter's driving ratio between two of its members from one speed to a faster speed, comprising the combination of a centrifugally operable friction clutch unit for establishing said one driving ratio; a positive clutch unit for establishing said faster speed engageable only when its two positive clutch members are operating substantially in synchronism and centrifugally operable means for actuating one of the two positive clutch members into engaged position, and a friction clutch in series with said centrifugally actuatable positive clutch having solely resilient means tending to engage same and having means for forcing its disengagement at will forming a flexible coupling in tandem with the coupling establishable by said centrifugally actuatable positive clutch whereby the speed established by the latter may be abnormally disestablished at will without molesting said positive clutch and without immobilizing the driving connections of said faster speed.

27. In a clutch mechanism having driving and driven members, a restraining mechanism normally adapted to hold said clutch in an open state by preventing movement of one of said members toward the other of said members, means operable under certain conditions to render said restraining mechanism ineffective to hold said clutch in an open state, means adapted under certain conditions to urge at least one of said clutch members toward the other of said clutch

members, and at least one of said certain conditions being fulfilled when one of said clutch members exceeds a predetermined speed of rotation.

28. In a clutch mechanism having driving and driven members, a restraining mechanism normally adapted to hold said clutch in an open state by preventing movement of one of said members toward the other of said members, speed responsive means operable to render said restraining mechanism ineffective to hold said clutch in an open state, speed responsive mechanism acting to urge at least one of said clutch members toward the other of said clutch members, the latter means adapted to place the clutch member it acts upon under considerable force tending to move said clutch members together before the first said speed responsive means renders said restraining mechanism ineffective whereby engagement of said clutch is substantially instantaneous to bring the clutch elements to a substantially full torque holding capacity to prevent prolonged slip periods in connection with the engagement of said clutch under torque.

29. In a multi-clutch mechanism adapted to be positioned in series in a circuit for transmitting drive when all of the units of said clutch are engaged, the combination comprising a positive clutch unit for connecting one pair of members of said circuit and engageable only when the said pair of members are operating in substantial synchronism, speed responsive means to engage said clutch, a slippable clutch unit for connecting another pair of members of said circuit for forming flexible coupling means in said circuit for opening and closing the latter without immobilizing the driving connection established by the positive clutch.

30. A multi-coupling mechanism for use in a circuit including parallel power flow lanes comprising a plurality of coupling mechanisms to be positioned at different interruptions in said cir-

cuit for transmitting drive through said circuit when both of said couplings are engaged, one of said coupling mechanisms comprising a positive clutch unit for connecting one pair of members of said circuit and engageable only when its two members are operating in substantial synchronism, means to engage said clutch, another of said coupling mechanisms comprising a slippable coupling unit for connecting another pair of members of said circuit thereby forming flexible coupling means in said circuit for opening and closing the latter without immobilizing the driving connection established by the positive clutch.

31. In a clutch mechanism, a driving member, 15 a plurality of driven members, power actuated means to cause relative engaging movement between friction elements on said driving member and similar elements on said driven members to cause said driving member to drive all of said driven members, and means operable independently of the power actuated means selectively to prevent or permit relative engaging movement between some of the friction elements on said driving member and the similar elements on at least one of said driven members while permitting relative engaging movement between the other friction elements on said driving and driven members, whereby said power actuated means can be used to pack the whole clutch mechanism or only a portion thereof.

32. In a multiple clutch, a pair of clutch driven plates, a pair of clutch driving plates positioned between the driven plates, power operated means to force said driving plates apart for engagement with both of said driven plates, and means to prevent engaging movement of one of said driving plates until after the other of said driving plates has been packed against its driven plate.
